UNITED STATES PATENT OFFICE.

HENRY PAULETT, OF YSTALYFERA, WILLIAM AUBREY JONES, OF SWANSEA, AND RICHARD WILLIAM OWEN, OF NEATH, WALES.

HOT-PLATE APPARATUS.

Application filed April 29, 1924. Serial No. 709,919.

To all whom it may concern:

Be it known that we, HENRY PAULETT, of 11 Lodge Buildings, Ystalyfera, in the county of Glamorgan, Wales, WILLIAM AUBREY JONES, of 75 Rhyddings Park Road, Swansea, in the county of Glamorgan, Wales, and RICHARD WILLIAM OWEN, of 21 Cimla Road, Neath, in the country of Glamorgan, Wales, subjects of the King of Great Britain, having invented certain new and useful Improvements in or Relating to Hot-Plate Apparatus, do hereby declare that the following is a full, clear, and exact description of the same.

15 This invention relates to hot-plates, or ovens, particularly for the use of bakers and pastry-cooks, and has for its object to provide an apparatus which shall be simple in construction and so may be cheaply 20 manufactured, and efficient in use, a characteristic feature being that the temperature of the hot-plate may be regulated or adjusted to a nicety.

In carrying out our invention, there is 25 provided a structure which comprises or includes a preferably fire-brick lined furnace, and a horizontal flue or chamber of appropriate length which is divided by means of a longitudinal partition or baffle- 30 plate into two portions, the lower portion being hereinafter termed, for convenience of reference, "baffle-plate chamber," and the upper portion "hot-plate chamber."

In said baffle-plate there are formed at 35 suitable intervals a plurality of ports or openings of desired size and shape or configuration, each port or opening being controlled by means of a damper plate or valve.

The top of said horizontal flue, which is 40 preferably of cast iron, constitutes a hot plate.

The structure may include a smoke box whereto is connected the lower end of a stack, or uptake, in which there is fitted an 45 externally-actuated draught-regulating closure member.

We will further describe our invention with the aid of the accompanying sheet of explanatory drawings which illustrate, by 50 way of example only, one mode of carrying the invention into effect.

In said drawings:

Fig. 1 is a part-sectional elevation of the apparatus, Fig. 2 being an end elevation, and Fig. 3 is a part-sectional plan. Fig. 4 is

a transverse section taken as on line A—A Fig. 3, drawn to an enlarged scale as compared with the preceding views, and Figs. 5 and 6 are details also drawn to an enlarged scale.

a designates a furnace with fire bars b, and fire door c. Said furnace communicates with a horizontal flue d, e and a smoke box f whereto is connected the lower end of a stack or uptake g in which there is fitted a draught-regulating disc h adapted to be actuated by means of an external handle i.

k indicates a longitudinal partition or baffle-plate which divides the flue d, e into two portions, a baffle-plate chamber d and a hot-plate chamber e; and l, l are ports formed in said horizontal partition or baffle plate k. m, m are damper plates which are slidable in side guides n and may be individually operated through link connections o by the aid of handles p.

The cast-iron top q of the flue constitutes a hot-plate. Said smoke box f is provided with a door r in order that access to said 80 chambers d, e may be readily obtained for the purpose of inspection and cleaning.

In use, the hot gases produced by the burning of fuel in the furnace a ascend to said baffle-plate chamber d and from thence are admitted to the hot-plate chamber e accordingly as to which of the ports l of the baffle-plate k are uncovered and the extent of the openings. Thus, by adjusting some or all of said dampers m in appropriate relationship with their ports l the temperature of the hot plate q may be regulated to exact requirements for baking or cooking.

The walls of said baffle-plate and hot-plate chambers d, e are preferably filled or lined with silicate cotton, or other suitable heat insulating material, and the end of the baffle-plate chamber d remote from the furnace a is provided with a door d'.

What we claim as our invention, and desire to secure by Letters Patent is:

1. A hot plate apparatus comprising a horizontal chamber the top wall of which is adapted to serve as a hot plate, a furnace communicating with said chamber, a horizontal partition in said chamber provided with a plurality of openings, and individual dampers for said partition openings.

2. An apparatus as called for in claim 1,

wherein said dampers are slidable on said partition and operatable from the front side of said apparatus.

3. A hot plate apparatus comprising a horizontal chamber, the top wall of which is adapted to serve as a hot plate, a furnace at one end of said chamber, a smoke box at the opposite end of said chamber, a horizontal partition in said chamber, said 10 horizontal partition having openings, a door at one end of said partition controlling communication between the lower part of said chamber and said smoke box, and means

slidable on said partition adapted for closing the partition openings.

4. A hot plate apparatus as called for in claim 3, wherein said means includes individually operated dampers.

In testimony whereof we affix our signatures in the presence of two witnesses.

HENRY PAULETT.

WILLIAM AUBREY JONES.

RICHARD WILLIAM OWEN.
